UNITED STATES PATENT OFFICE.

WILLIAM LEE PILKINGTON, OF ST. HELENS, COUNTY OF LANCASTER, ENGLAND, ASSIGNOR TO PILKINGTON BROTHERS, OF SAME PLACE.

DESIGN FOR THE ORNAMENTATION OF GLASS.

SPECIFICATION forming part of Design No. 19,552, dated December 31, 1889.

Application filed December 7, 1889. Serial No. 332,968. Term of patent 14 years.

To all whom it may concern:

Be it known that I, WILLIAM LEE PILKINGTON, of St. Helens, in the county of Lancaster, Kingdom of Great Britain, a subject of the Queen Britain, have invented and produced a new and original Design for the Ornamentation of Glass, of which the following is a specification, reference being had to the accompanying drawings, forming part thereof.

Figure 1 is a plan view of a plate of glass showing my design, and Fig. 2 is an edge view of the same, these two views being deemed necessary to fully illustrate my design.

The leading feature of my design consists in a raised surface composed of parallel series of similar short plane-faced bands or stripes located opposedly endwise of each other in each series; of parallel series of similar short corrugated-faced bands or stripes located opposedly endwise of each other in each series, and with the series thereof alternating with and the bands or stripes of such alternating series overlapping the ends edgewise of the plane-faced bands or stripes of the series thereof, and parallel series of similar short corrugated-faced bands or stripes located opposedly endwise of each other in each series and at right angles to and between the opposed ends of the bands or stripes of the said respective and alternate parallel series of plane-faced and corrugated-faced bands or stripes.

A A A are similar short plane-faced bands or stripes located opposedly endwise of each other and arranged in parallel series.

B B B are similar short corrugated-faced bands or stripes located opposedly endwise of each other and arranged in parallel series, the several series thereof alternating with the series of plane-faced bands or stripes,

and the bands or stripes of the alternating series overlapping at the ends edgewise, as shown.

C C C are similar short corrugated-faced bands or stripes located opposedly endwise of each other in parallel series and at right angles to and between the opposed ends of the bands or stripes A A A of the series thereof and of the bands or stripes B B B of the series thereof.

These bands or stripes A A A, B B B, and C C C, respectively parallel in series and located relatively to each other as described, extend over the face of a plate of glass D as a raised surface thereon.

What I claim is—

The design for an ornamentation of glass herein shown and described, the same comprising parallel series of similar short plane-faced bands or stripes A A A, located opposedly endwise of each other in each series, parallel series of similar short corrugated-faced bands or stripes B B B, located opposedly endwise of each other in each series and with the series thereof alternating with and the bands or stripes of such alternating series overlapping the ends edgewise of the plane-faced bands or stripes of the series thereof, and parallel series of similar short corrugated-faced bands or stripes C C C, located opposedly endwise of each other in each series and at right angles to and between the opposed ends of the bands or stripes A A A and B B B, respectively, of the respective and alternate parallel series thereof, as set forth.

WM. LEE PILKINGTON.
